UNITED STATES PATENT OFFICE.

TOWNSEND C. BUDD, OF AKRON, OHIO, ASSIGNOR OF ONE-HALF TO MARKLE & INMAN, OF SAME PLACE.

JOLLIE AND JOLLIE-MOLD.

SPECIFICATION forming part of Letters Patent No. 415,448, dated November 19, 1889.

Application filed March 3, 1888. Serial No. 266,112. (No model.)

To all whom it may concern:

Be it known that I, TOWNSEND C. BUDD, a citizen of the United States, residing at Akron, in the county of Summit and State of Ohio, 5 have invented a certain new and useful Jollie and Jollie-Mold, of which the following is a specification.

My invention has relation to improvements in that class of crock-turning machines known 10 as "jollies," in which a metallic cup-shaped head mounted on and revolved by a vertical shaft receives successively crock-molds of plaster-of-paris, which, by means of an annular shoulder, rest on the upper edge of the 15 head and revolve with it, the molds having proper internal shape to form the outside of the crock, and in which plastic clay is placed and turned to the desired thickness, when 20 they are successively removed with the green crock inside, and placed where by drying the crock will shrink and separate from the mold. This construction and process is objectionable 25 because, ordinarily, a separate head is required for each size of mold, and as a day is commonly necessary to sufficiently dry the crock to permit its removal from the mold the number of molds must equal the daily product. It is also objectionable because the crock when removed is so dry that it is difficult 30 to attach the handles, and because the molds, being unprotected, are frequently broken.

The objects of my invention are to overcome these objections by the construction of 35 a jollie-head in which molds for different sizes of crocks may be used, and molds to be used therewith of such construction that they will be protected against breakage, and from which the crock will separate in a few minutes 40 and be left in a green state suitable to receive the handles.

My invention consists in the devices illustrated in the accompanying drawings, as hereinafter described and claimed.

45 In the accompanying drawings, in which similar letters of reference indicate like parts, Figure 1 is vertical central section of a jollie-head; Fig. 2, an elevation of the crock, mold-bottom, and port, the mold-body in vertical

central section; Fig. 3, a set of rings to adjust the head to different forms of mold.

The head A, mounted on the vertical shaft B, is substantially the same in shape as those in common use, but has on the inside two rims a a', near the top and bottom, respectively, on which rest two flat rings e e', which fit the internal diameter of the head at these points, and the openings of which fit the mold.

The mold consists of an outer case C of metal, usually of cast-iron, and with an orifice 60 in the bottom with sloping sides in which fits a metallic plate c, on the bottom of which are two cleats i i. The inside of the case C and plate c have linings of plaster-of-paris D d, respectively, which constitute the mold for 65 the outside of the crock, the edges of the lining d being sloped at substantially the same angle as the edges of the plate c, with the top of the same size as the interior of the lining D. There is thus formed a complete mold 70 for the outside of the crock, with a bottom that can be forced up through the body, and the parts of which are prevented from breaking by their metallic supports.

In operation, the proper rings e e' having 75 been placed in the head, the mold is fitted therein and a crock of plastic clay turned in it in the usual manner. Near the jollie is a number of fixed posts with flat heads, one whereof F is shown in Fig. 2. The crock 80 having been turned, the mold is removed from the head and placed on the post F and the operation repeated with another mold. In a short time, varying from one-half to an hour, the crock dries and shrinks sufficiently to 85 permit it to separate from the body of the mold, which falls straight down around the post, leaving the pot and bottom d on the post, as shown in Fig. 2, whence they are removed to any suitable place, the cleats i i 90 supporting the plate c sufficiently to permit the hands to pass under it. By this arrangement the number of molds required for any given number of crocks is materially lessened, as the same molds can be used several times 95 each day, separate bottoms for each crock only being needed, and the crock is released in a green state suitable to receive handles,

while by the use of different rings *e e'* different sizes of molds can be used in the same head.

I claim as my invention—

- 5 1. A jollie having an outer metallic body with an opening in the base having upward outwardly-sloping edges, and lined with plaster-of-paris to determine the shape of the molded article, and having a loose metallic
- 10 plate set in the opening in its base, removable upward from its seat, substantially as shown and described, and for the purpose specified.

2. The combination, with a jollie-head having upper and lower internal flanges and a jollie less in diameter than said head, of two ¹⁵ rings interposed between said flanges and jollie to support the latter within the former, substantially as shown and described.

In testimony that I claim the above I hereunto set my hand.

TOWNSEND C. BUDD.

In presence of—
C. P. HUMPHREY,
D. W. HUMPHREY.
